(57) **CLAIM**

The ornamental design for a strapping tool, as shown and described.

DESCRIPTION

FIG. 1 is a front top right-side perspective view of the strapping tool;

FIG. 2 is a front bottom right-side view thereof;

FIG. 3 is a front elevation view thereof;

FIG. 4 is a rear elevation view thereof;

FIG. 5 is a right-side view thereof;

FIG. 6 is a left-side view thereof;

FIG. 7 is a top plan view thereof; and,

FIG. 8 is bottom plan view thereof.

The broken lines showing parts of the strapping tool form no part of the claimed design.

1 Claim, 8 Drawing Sheets
